UNITED STATES PATENT OFFICE.

MARTIN C. DE BOTELHO, OF NEW YORK, N. Y.

DESIGN FOR A VANITY CASE.

Application filed March 19, 1927. Serial No. 21,211. Term of patent 7 years.

To all whom it may concern:

Be it known that I, MARTIN C. DE BOTELHO, a citizen of Brazil, and a resident of the city of New York, borough of Manhattan, in the county and State of New York, have invented a new, original, and ornamental Design for Vanity Case, of which the following is a specification.

Reference is to be had to the accompanying drawing in which

Figure 1 is a perspective view of a vanity case showing my new design, and as viewed from the front;

Fig. 2 is a perspective view thereof as viewed from the rear.

I claim—

The ornamental design for a vanity case as shown.

MARTIN C. DE BOTELHO.
